UNITED STATES PATENT OFFICE.

JOE S. MCKIBBON, OF LOS ANGELES, CALIFORNIA.

WRENCH.

1,423,499.

Specification of Letters Patent. Patented July 18, 1922.

Application filed February 9, 1922. Serial No. 535,210.

To all whom it may concern:

Be it known that I, Joe S. McKIBBON, a citizen of the United States, residing at Los Angeles, in the county of Los Angeles and State of California, have invented new and useful Improvements in Wrenches, of which the following is a specification.

My invention relates to wrenches, and a purpose of my invention is the provision of a wrench having a stationary jaw and a movable jaw associated with the stationary jaw to occupy advanced and retracted positions, and adapted to automatically occupy an advanced position when operating a nut where- 10 by the two jaws are caused to securely grip the nut and positively prevent the slipping of the wrench upon the nut and the consequent injury of the operator's hands.

Although I will describe only one form of wrench embodying my invention and point out the novel features thereof in claims, it is to be understood that various changes and modifications may be made herein without departing from the spirit and scope of such 25 claims.

In the accompanying drawings,

Figure 1 is a view showing in side elevation and partly in section one form of wrench embodying my invention.

30 Fig. 2 is a view similar to Fig. 1 with the handle broken away.

Fig. 3 is a detail perspective view with the connecting link comprised in the wrench shown in the preceding views.

35 Fig. 4 is a detail perspective view of the connecting stud comprised in the wrench shown in the preceding views.

Referring specifically to the drawings in which similar reference characters refer to 40 similar parts, my invention, in its present embodiment, comprises a stationary jaw J and a movable jaw J', the two jaws being provided on the confronting faces with rear- 45 wardly extending serrations 15, and integrally formed shanks 16 and 17, respectively, with the shank 16 being extended to provide an operating handle or bar 18. At corre- 50 sponding points adjacent the jaws J and J', the shanks 16 and 17 are formed with open- 55 ings 16^a and 17^a, respectively, in which is loosely received a connecting stud S. As clearly shown in Fig. 1, the connecting stud is formed at its lower end with an annular shoulder 19 adapted to loosely seat within 60 the correspondingly shaped enlargement 20 of the opening 16^a. The upper end of the

stud extends into the opening 17^a and is provided with a screw-threaded bore 21 in which is received an adjusting screw K having a knurled head of sufficient size to prevent the 60 passage of the screw downwardly through the opening 17^a.

The shanks 16 and 17 are notched at opposite edges as indicated at 22 and 23, respectively, and these notches receive pins 24 and 65 25 constituting a portion of a connecting link designated generally at L and including ovate plates 26 rigidly connected to each other by the pins 24 and 25.

From the foregoing arrangement it will 70 be clear that the connecting link L provides means for movably associating the jaw J' with respect to the jaw J and in such manner as to allow of the jaw J' occupying a re- 75 tracted or projected position as shown in Fig. 1 or an advanced position as shown in Fig. 2, it being understood that the loose fitting of the stud within the openings 16^a and 17^a allows of the necessary movement of the 80 jaw J' to occupy these two positions.

The screw K co-operates with the connecting stud S in providing adjusting means for the jaw with respect to the jaw J to allow of the wrench being accommodated to nuts of different sizes. To normally maintain the jaws in expanded position and thereby effect the proper operation of the screw K, a leaf spring D is secured to the inner edge of the shank 16 by means of a rivet 27, and this spring is bent 90 longitudinally so that its free end bears against the shank 17 at a point adjacent the opening 17^a thereby urging the jaw J' outwardly so that its shank engages the 95 head of the screw K.

In operation, the wrench is first adjusted by a manipulation of the screw K to space apart the jaws J and J' to the required distance whereupon the wrench is applied in the usual manner. If the jaw J' is in the 100 projected position as shown in Fig. 2 when the wrench is applied to the nut, the frictional contact of the jaw with the nut will move the jaw rearwardly to the retracted position shown in Fig. 1. Consequently 105 when lateral pull is exerted on the bar 18 in effecting rotation of the nut, the serrations 15 of the jaw J' grip the nut and thereby cause the jaw J' to move to the projected position shown in Fig. 2. With jaw 110 J' in this position, it will be clear that it effectively co-operates with the jaw J in

positively presenting disengagement or movement of the jaws with respect to the nut so that the possibility of the wrench slipping from the nut is prevented.

5 It will be manifest that the secure gripping of the jaws is obtained by virtue of the fact that when the jaw J' is in projected position its serrated surface is in parallelism with the serrated surface of the jaw J 10 so that the two surfaces grip the faces of the nut with pressure which is uniform throughout the length of such surfaces.

What I claim is:

1. A wrench comprising a stationary jaw, 15 a movable jaw associated with the stationary jaw to occupy a retracted position in which the faces of the jaws are disposed in converging relation to each other, and a projected position in which said faces are 20 disposed in spaced parallelism, means for automatically opening the jaws, and adjustable means for limiting the opening action.

2. A wrench comprising a stationary jaw, 25 a movable jaw associated with the stationary jaw to occupy a retracted position in which the faces of the jaws are disposed in converging relation to each other, and a projected position in which said faces are 30 disposed in spaced parallelism, and loose coupling means for adjusting the movable jaw with respect to the stationary jaw irrespective of the position of the former, and passing through the jaws.

3. A wrench comprising stationary and 35 movable jaws, shanks formed on the jaws, a connecting link associated with said shanks to allow the movable jaw to occupy retracted and projected positions with respect to the stationary jaw, and means passing 40 through and for adjusting said jaws with relation to each other.

4. A wrench comprising stationary and 45 movable jaws, shanks formed on the jaws, a connecting link associated with said shanks to allow the movable jaw to occupy retracted and projected positions with respect

to the stationary jaw, a connecting stud loosely sustained in the shank of the stationary jaw, a screw threadedly engaging the stud and loosely fitted within the shank 50 of the movable jaw, and a spring interposed between the shanks for urging the movable jaw outwardly with respect to the stationary jaw.

5. A wrench comprising stationary and 55 movable jaws, shanks for the jaws having recesses formed therein and a connecting link including plates and pins connecting the plates, said pins being rockably mounted in said recesses, a connecting stud loosely 60 sustained in the shank of the stationary jaw, a screw threadedly engaging the stud and loosely fitted within the shank of the movable jaw, and a spring interposed between the shanks for urging the movable 65 jaw outwardly with respect to the stationary jaw.

6. A wrench comprising a pair of opposed jaws having extended shanks, means 70 pivotally connecting the extended shanks to permit one of the jaws to shift longitudinally as to the other jaw and forming a sliding connection, and a coupling device passing through the jaws and providing for the said longitudinal relative movement 75 and forming means for limiting separation of the swinging ends of the jaws.

7. A wrench comprising a pair of opposed jaws having extended shanks, means 80 pivotally connecting the extended shanks to permit one of the jaws to shift longitudinally as to the other jaw and forming a sliding connection, a coupling device passing through the jaws and providing for the said longitudinal relative movement 85 and forming means for limiting separation of the swinging ends of the jaws, and means for automatically spreading the jaws.

In testimony whereof I have signed my name to the specification.

J. S. McKIBBON.
